T. E. STURTEVANT,
RELIEF VALVE FOR ROCK DRILLS,
APPLICATION FILED JAN. 30, 1914.

Patented Feb. 9, 1915.

Fig. 1.

UNITED STATES PATENT OFFICE.

THOMAS E. STURTEVANT, OF DOVER, NEW JERSEY, ASSIGNOR TO MCKIERNAN-TERRY DRILL COMPANY, OF DOVER, NEW JERSEY, A CORPORATION OF NEW JERSEY.

RELIEF-VALVE FOR ROCK-DRILLS.

1,127,823.

Specification of Letters Patent

Patented Feb. 9, 1915.

Application filed January 30, 1914. Serial No. 315,362.

To all whom it may concern:

Be it known that I, THOMAS E. STURTEVANT, a citizen of the United States of America, and a resident of Dover, Morris county, and State of New Jersey, have invented certain new and useful Improvements in Relief-Valves for Rock-Drills, of which the following is a specification, reference being had to the accompanying drawings, forming a part thereof.

My invention relates to elastic fluid engines, and particularly to power-operated percussive tools such as rock drills, mining machines and the like, the operation of which is effected by elastic motive fluid under pressure alternately admitted into a working cylinder upon opposite sides of a reciprocating piston freely mounted therein.

One object of my invention is to provide in a device of the aforesaid character, simple and effective means for stopping the machine and blowing fluid through an opening in the drill steel, for the purpose of cleaning the cuttings out of the drill hole.

Another object of my invention is to provide a readily operated attachment for producing an unbalanced fluid pressure condition in the valve chest of a drill and causing the valve to move the plunger to the back end of its stroke and hold it in such position.

Other objects and advantages of my invention will be set forth hereinafter, and in order that my invention may be thoroughly understood, I will now proceed to describe the same in the following specification, and then point out the novel features thereof in appended claims.

Referring to the drawings: Figure 1 is a central longitudinal section of a rock drill equipped with my invention. Fig. 2 is a view corresponding to the middle portion of Fig. 1, illustrating the positions of the parts when the attachment is actuated. The relief valve of my invention and the end of the valve chest to which it is attached are shown in section on a larger scale in Fig. 3. Fig. 4 is a sectional view of the relief valve attachment taken on the line 4-4 of Fig. 3. Fig. 5 is a sectional plan view of the same, taken on the line 5-5 of Fig. 4.

In the operation of rock drills it becomes necessary at frequent intervals to clean out the cuttings from the hole since they otherwise impede the progress of the drill. With the attachment of my present invention, it

is only necessary for the operator to actuate a push button, in order to stop the machine and direct a blast of the motive fluid outwardly through a hole in the drill steel, the machine being started automatically as soon as pressure is removed from the push button.

My improvement may be utilized with drills and similar mechanisms of various kinds and while I have shown a particular form of drilling machine, my invention is in no way restricted thereto.

The machine illustrated comprises a cylinder 10 in which operates a piston or plunger 12 having a striker or hammer 14 at one end, a valve chest 16, a slide valve 18 therein, and my improved relief valve 20 at one end of the chest. The drill is arranged to operate in a well known manner and need not be described in detail. Motive fluid is supplied to the valve chest at 17-17^a and is exhausted from the machine at 11. Ports 19 and 19^a connect the valve chest with the respective ends of the main cylinder 10 and the usual ports 21 and 21^a connect each one of the valve chests with the opposite end of the main cylinder. A cap 22 is secured to one end of the chest and an end plate 23 at the opposite end. This end of the chest is shown on a larger scale in Fig. 3. It has secured to it the valve 20. The end of the valve chest is counterbored at 24, and a thimble 25 set into it. The thimble has a central hole 26 and a cylindrical projection 27 which extends into a central hole 28 in the end plate 23, a yielding washer 29 being fitted on the cylindrical projection 27 and interposed between the thimble and the plate. The hole 28 in the plate is enlarged at its upper end to form a recess 30 and a valve seat 31 is mounted on the plate and has a projection 32 which extends into the recess 30. The seat 31 has a central opening 33 of conical form into which a tapered plug valve 34 is inserted. This valve extends beyond the end of the seat and constitutes a projection or button which may be pressed to open the valve.

The valve is held on its seat by a spring 35 which is interposed between the thimble 25 and the valve 34. The valve seat 31 and the plate 23 are both held in position by bolts 36 which extend through these members in the usual manner and are screwed into the valve chest. The valve seat is preferably provided with a cross-passage or outlet 40 as clearly shown in Figs. 4 and 5 and

the valve is provided with an annular groove 41 and perforations 42 and 43 which form connecting passages. The arrangement of parts is such that the valve may be 5 pressed inwardly in opposition to the spring 35 and when so pressed opens a free passage from the end of the chest through the hole 26, the hole 28 and the passages 43 to 40 inclusive, to the atmosphere. Motive fluid 10 under pressure in the end of the valve chest is thus quickly exhausted. The effect of this action will be evident from the operation of the machine which will now be described: Assuming that the parts occupy 15 the positions in which they are illustrated in Fig. 1, fluid pressure being then admitted from the valve chamber 17 through the passage 19 to the upper end of the cylinder 10,—the plunger is thus moved 20 downwardly and the striker is about to deliver a blow to the end of the drill which is indicated at 13. The lower end of the cylinder is connected through passage 19^a in the usual manner to the exhaust 11. 25 When the plunger reaches the limit of its movement in this direction the end of the passage 21 is uncovered and is connected to exhaust by a circumferential groove 45 of the piston. The pressure in the upper end 30 of the valve chest which existed by reason of the leakage from the inlet chamber 17 through a smaller opening 18^a in the slide valve, is therefore relieved. The pressure in the inlet chamber 17^a consequently forces 35 the slide valve to its upper position and connects the lower end of the main cylinder with the inlet chamber 17^a through the passage 19^a, the end of the main cylinder being then connected to exhaust through passage 40 19. The arrangement of parts and the size 45 of the passage 21 and 21^a are such that the pressure is relieved gradually from the ends of the chest.

While the machine is in operation the attendant may press the extremity of the valve 34 with his finger in opposition to the spring 35 and as above described, a free passage will immediately be established from the adjacent end of the valve chest to 50 the atmosphere. These passages are sufficiently large to quickly relieve the pressure in the end of the chest and to cause an upward movement of the slide valve in such a direction as to hold the main piston or plunger in its elevated position as shown in 55 Fig. 2. In this position, as clearly indicated, a connection is established directly

from the inlet chamber 17^a of the chest through the passage 19^a into the lower end of the cylinder, thence through spaces between the striker and a sleeve or bushing 48 in which it operates, and out through a central hole 49 in the drill. The striker 14 is fluted or otherwise arranged to permit the motive fluid to pass freely through the 60 sleeve 48. By this means a strong blast is produced which quickly and effectively cleans the drill hole. As soon as pressure is relieved from the valve 34, the valve will be closed by the spring 35 and the tool will 65 resume its operation.

What I claim is:

1. In a rock drill, the combination with a cylinder, a plunger therein, a valve chest, a floating slide valve for governing the supply of fluid to the cylinder, and a hollow 75 drill steel, a relief valve biased to closed position and controllable by the operator for exhausting the fluid pressure from one end of the valve chest to stop the drill and blow motive fluid through the drill steel.

2. In a rock drill, the combination with a cylinder, a plunger therein, a valve chest, a floating slide valve for governing the supply of fluid to the cylinder, and a hollow 85 drill steel, a push button relief valve, a spring tending to hold the valve closed, and an outwardly extending valve stem controllable by the operator for opening the valve and exhausting the fluid pressure from one 90 end of the valve chest to stop the drill and blow motive fluid through the drill steel.

3. In a rock drill, the combination with a cylinder, a plunger therein, a valve chest, a floating slide valve for governing the supply of fluid to the cylinder, and a hollow 95 drill steel, a push button relief valve comprising a valve seat constituting a cap secured to the valve chest and having an outwardly converging taper hole, a taper plug 100 seated therein and projecting beyond the seat, a spring tending to seat the plug, said stem being controllable by the operator for opening the valve and exhausting the fluid pressure from one end of the valve chest to 105 stop the drill and blow motive fluid through the drill steel.

In witness whereof, I have hereunto set my hand in the presence of two subscribing witnesses, this 26 day of January, 1914.

THOMAS E. STURTEVANT.
